UNITED STATES PATENT OFFICE.

JOHANN KOENIG, OF RIGA, RUSSIA.

EQUILIBRIUM STOP-VALVE.

933,468.

Specification of Letters Patent. Patented Sept. 7, 1909.

Application filed October 8, 1908. Serial No. 456,442.

To all whom it may concern:

Be it known that I, JOHANN KOENIG, engineer, a subject of the King of Bavaria, residing at 97 Alexanderstrasse, Riga, Russia, have invented new and useful Improvements in Equilibrium Stop-Valves, of which the following is a specification.

The subject of my invention is a stop-valve, whose valve-body comprises two telescopic cylindrical members, making a tight joint with each other. The one member is stationary, while the other, which is provided with a seating-face, can slide by being connected to the valve-stem by means of a lever device. The sliding member is furnished with apertures to admit the steam or other fluid to the interior of the valve-body, for the purpose of balancing the valve.

According to my invention not only is the valve balanced, but free in- and out-flow of the steam or liquid without shocks is insured, and there is no obstruction of the passage of flow by the actuating device.

Two forms of construction of the new valve are illustrated in the accompanying drawings.

Figure 1 is a longitudinal section through the one construction. Fig. 2 is a cross section on the line A—B of Fig. 1. Fig. 3 is a longitudinal section through a modification. Fig. 4 is a cross section on the line A—B of Fig. 3.

In Figs. 1 and 2, *a b* is the casing containing the valve-body. The latter comprises two hollow cylindrical telescopic parts *c d*, the exterior ends being conical, so that no detrimental obstruction is offered to the in- and out-flowing current of steam or liquid. The exterior part *c* is integral with the casing *a*, while the interior part *d* slides within the part *c*. This part *d* is furnished with a ring *z* presenting a seating-face *f*, adapted, on the valve being closed, to make a tight joint with the seat *e* of the casing-part *b*. The part *d* butts against a plate *r*, *p* being packing material between the two. From the plate *r* there projects the rod *s*, and the rod and plate are secured to the part *d* by studs *u*, passing through a flange *t* of the rod and screwed into the plate *r* and part *d*. The rod *s* presents an eye *v* and into this there takes the longer arm of a bent lever *m*, pivoted by a pin *x* to the lugs *y* pendent from the cover of the casing *a*. The shorter lever-arm has a forked end which embraces

the stem *g*, rotated by a handwheel *h*. By turning the handwheel *h*, the part *d* of the valve-body can obviously be approached to or retracted from the seat *e* of the casing-part *b*, as desired. In this manner the valve-passage can be adjusted as required, or the valve wholly closed or opened. The part *d* is perforated at *i j* and the plate *r* at *k*, so that the steam or liquid can flow through the apertures to the chamber *o* of the casing, whereby the valve is balanced.

In the modification shown in Figs. 3 and 4 the arrangement illustrated in Figs. 1 and 2 is reversed, the inner part *c'* being here stationary while the outer part *d'* slides. *p'* is packing located between the part *c'* and the plate *r'*. In this modification the outer part *d'* presents a seating-face *f'*, adapted to make a tight joint with the seat *e'* of the part *a'* of the casing *a' b'*. The valve actuating parts *m g h* are substantially the same as in the construction illustrated in Figs. 1 and 2, the longer lever arm, however, being pivoted to the sliding part *d'* by means of a link *s'*. To insure balancing of the valve the parts *c' d'* are provided with apertures *i' j'*, and the plate *r'* furnished with an aperture *k'*.

Having thus described my invention, I declare that what I claim is:

1. An equilibrium stop valve for pipe conduits, comprising a valve casing, and a relieving casing firmly connected with and placed in the said valve casing and concentrically arranged around the pipe axis with a concentric annular space for the flow of the fluid therebetween, a slidably arranged valve-cone on the exterior of said relieving casing, whose movement axis coincides with the pipe axis and an angle lever for giving movement to said valve-cone.

2. An equilibrium stop valve for pipe conduits, comprising a valve casing, and a relieving casing firmly connected with and placed in the said valve casing and concentrically arranged around the pipe axis with a concentric annular space for the flow of the fluid therebetween, a slidably arranged valve-cone on the exterior of said relieving casing, whose movement axis coincides with the pipe axis and an angle lever for giving movement to said valve-cone, said valve casing, relieving casing and valve-cone having such shape that the passage therebetween causes only gradual alterations in speed as

well as in the direction of flow of the fluid, so that the flowing resistance is reduced to the smallest possible degree.

3. An equilibrium stop valve comprising
- 5 a casing with valve seat, a stationary cylindrical member located in the casing, a perforated cylindrical member telescoping therewith and having communication with the interior thereof and having a seating
  - 10 face fitted to said valve seat, a screw stem passed through the wall of the casing, a bent

lever pivoted to the wall of the casing outside the fluid-passage and having its arms jointed respectively to said stem and telescoping member.

15

In witness whereof I have hereunto signed my name this 23rd day of September 1908, in the presence of two subscribing witnesses.

JOHANN KOENIG.
